CLAIM

The ornamental design for a display screen with graphical user interface, as shown and described.

DESCRIPTION

FIG. 1 is a front view of a first embodiment of a display screen with graphical user interface, showing the new design; and,

FIG. 2 is a front view of a second embodiment of a display screen with graphical user interface showing the new design. The dot-dash line showing of a display screen forms no part of the claimed design. The broken line showing of portions of the graphical user interface form no part of the claimed design.

1 Claim, 2 Drawing Sheets
